UNITED STATES PATENT OFFICE.

WILLIAM LEATCH, OF CANAL DOVER, OHIO.

BABBITT BOX.

SPECIFICATION forming part of Letters Patent No. 554,224, dated February 4, 1896.

Application filed June 13, 1895. Serial No. 552,705. (No model.)

To all whom it may concern:

Be it known that I, WILLIAM LEATCH, a citizen of the United States, and a resident of Canal Dover, county of Tuscarawas, State 5 of Ohio, have invented certain new and useful Improvements in Babbitt Boxes, of which I hereby declare the following to be a full, clear, and exact description, such as will enable others skilled in the art to which it applies 10 to make and use the same.

My invention relates to improvements in Babbitt-metal boxes or other soft-metal bearings for car-boxes; and the objects of the invention are to reinforce the brittle metal and prevent its breaking up when sudden strains 15 or shocks are brought to bear upon it, such as are incident to street-railway service, and, further, to provide passages or tubes through the boxes for the free admission and discharge 20 of liquid lubricants to the bearing, which shall also serve to retain a constant supply of lubricant and supply it to the bearing as fast as required.

My invention consists in metallic strengthening material or netting intermingling with the brittle Babbitt metal and novel-arranged continuous passages through the Babbitt from the exterior to the bearing-surface for liquid lubricant, as hereinafter described, shown in 25 the drawings accompanying, and specifically pointed out in the claims.

In the accompanying drawings, Figure 1 is a plan view of the bearing, the oil-conveying passages being indicated in dotted lines. Fig. 35 2 is a vertical longitudinal section through oil passages and reservoir, the reinforcing material being shown in dotted lines. Fig. 3 is a perspective view partially broken away to show the construction of the parts.

40 In the views, 1 is the Babbitt-metal bearing which is adapted to be placed over the axle with the curved side down to support the weight of the car. Through this Babbitt metal is arranged the reinforcing material, 45 which consists in metallic strands or netting 2, extending horizontally through the Babbitt from side to side.

In order to form an oil-reservoir within the box and improved passages through it to the 50 curved bearing-surface, a metal tube or continuous passage-way 3 is inserted or formed in the body of the metal, which is provided with narrow openings 4 on the upper side

and near one end of the box, for the insertion of oil. This passage-way 3 leads from 55 the openings downward a slight distance and thence horizontally through the box, thus forming a loop in the box near the end opposite to the openings 4.

In order to admit the oil in small quantities 60 to the curved bearing-surface at the part whence it can be most readily distributed to the axle, small apertures 5 of considerable less diameter than the tube are drilled from the bearing-surface into the tube, through 65 which the oil percolates on the bearings as fast as utilized, and the surface of the bearing is scored at 6 with grooves to assist in distributing the oil also. In the passages thus formed a great quantity of oil can be stored 70 for lubricating the axle and supplied thereto as rapidly as required.

The metal tubing may serve as a reinforcement for the soft metal and the number of tubes may be increased at pleasure. 75

The metal comprising the reinforcing material and tubes is preferably brass, which presents a good bearing-surface to the axle in case the metal of the bearing should wear away and expose the reinforcing metal to the 80 friction of the axle.

In constructing the bearing described the tube and the reinforcing metal are first placed in the mold so as to occupy their proper positions and the molten Babbitt is then poured 85 over them until the mold is filled.

Having described my invention, what I claim as new, and desire to protect by Letters Patent, is—

1. In combination with the Babbitt metal 90 of a car-axle bearing, metallic reinforcements cast into the body of the same, consisting in tubes traversing the bearing, provided with outer inlet-openings, and passages leading from said tubes to the surface of the bearing, 95 substantially as set forth.

2. In a soft and brittle metal bearing for car-axles, the combination, with the metal composing the bearing, of tough metal reinforcements therefor, cast therein, embracing 100 continuous tubes provided with inlet and outlet openings substantially as described.

WM. LEATCH.
